UNITED STATES PATENT OFFICE.

TRUMAN B. FUNK, OF MOLINE, AND WALTER L. CARVER, OF ROCK ISLAND, ILLINOIS,
ASSIGNORS TO MOLINE PLOW COMPANY, OF MOLINE, ILLINOIS, A CORPORATION
OF ILLINOIS.

INTERNAL-COMBUSTION ENGINE.

1,396,183.

Specification of Letters Patent.

Patented Nov. 8, 1921.

Application filed September 10, 1917. Serial No. 190,552.

To all whom it may concern:

Be it known that we, TRUMAN B. FUNK and WALTER L. CARVER, both citizens of the United States, residing at Moline, county of Rock Island, and State of Illinois, and at Rock Island, county of Rock Island, and State of Illinois, respectively, have invented certain new and useful Improvements in Internal-Combustion Engines, of which the following is a specification.

The present invention has to do with certain new and useful improvements in internal combustion engines, and has particular reference to the arrangements for feeding the elements of combustion in such a manner as to secure the best results of operation. The features of the present invention are very well adapted for use in connection with engines intended for burning kerosene, but it will appear from a study of the features of the invention that the said features will be of great benefit to any engine burning gasolene and many of the low grade fuels which are being used at the present time.

It is well understood that water, when injected into the cylinder of an internal combustion engine, prevents the accumulation of carbon and also has a very beneficial cooling effect upon the inner walls of the cylinder, thereby improving the lubrication, and bringing about a number of conditions that make for better operation and service.

Satisfactory introduction of the water into the cylinders of the engine has been a problem which has presented considerable difficulties in the way of a satisfactory solution. The water should be introduced at all times at the proper rate of feed according to the gas consumption of the engine, being introduced more rapidly when the engine is running rapidly than when the engine is running slowly. Manifestly it is not always possible for the operator to manually adjust or modify the rate of water feed from time to time, and it is, therefore, very desirable to provide an arrangement whereby the water feed will automatically regulate or vary according to the requirements of the instantaneous speed of operation of the engine.

One of the objects of the present invention is to provide an arrangement whereby

the rate of water feed will automatically vary from moment to moment according to the requirements of the engine speed. Furthermore, the water at no time is introduced at a high rate or volume, the amount of water taken in at any time being comparatively small. As a result the passages and valves for delivering and controlling the water are of necessity of somewhat small size, and in the past considerable difficulty has been experienced in so arranging the parts that small particles of dirt and foreign substances will not clog up the system. Another object of the present invention is to so arrange the water feeding system and mechanism that the danger of clogging by foreign substances will be minimized.

The best results of operation are found to be secured when the water is introduced into the cylinders in the form of steam mixed with the combustible mixture. This necessitates the generation of steam from the water and the introduction of this steam into the combustible mixture at a suitable point and in the proper quantities at all times. Therefore, another object of the invention is to provide an arrangement whereby the steam will be generated at all times in substantially the correct quantities for the best conditions of operation according to the instantaneous demands for gas.

Another feature of the invention has reference to the arrangement of the parts and their construction in such a manner that they may be standardized both as to form and size for engines of different sizes and characteristics. This will make it possible to meet the requirements of different sizes of engines with a minimum number of stock parts and consequently at a minimum cost of manufacture.

Another feature of the invention has to do with the introduction of the moisture into the air at that point which will give the best results of operation. We have found that, when the moisture is introduced into the air in the form of mixture and before the air reaches the carburetor, the results of operation are very much better than when the steam or moisture is introduced at any other point. This is particularly true when burning such fuels as kerosene and the like, because the fuel is thereby carburized or va-

porized in a very much more efficient manner. Therefore, another object of the invention is to provide an arrangement whereby the moisture may be introduced into the air in the form of steam and prior to the introduction of the air into the carbureter.

Other objects and uses of the invention will appear from a detailed description of the same which consists in the features of construction and combinations of parts hereinafter described and claimed.

Referring to the drawings:

Figure 1 shows a side elevation of a four cylinder internal combustion engine having applied thereto the features of the present invention. This is a view looking at the intake side of the engine, the exhaust manifold, as well as certain other parts, being shown in dotted lines;

Fig. 2 is an end view of the machine shown in Fig. 1;

Fig. 3 is a fragmentary vertical section through the exhaust manifold and air jacket surrounding the same;

Fig. 4 is a vertical cross section taken on line 4—4 of Fig. 3, looking in the direction of the arrows;

Fig. 5 is a horizontal section taken on the line 5—5 of Fig. 2, looking in the direction of the arrows;

Fig. 6 is a view similar to Fig. 5, showing a modified construction of parts; and

Fig. 7 is a vertical section taken approximately on the line 7—7 of Fig. 5, looking in the direction of the arrows.

Before proceeding with a detailed description of the construction shown in the drawings, we will state that in a simple application of the principles of the present invention use is made of a water box heated by the exhaust gases from the engine, so as to generate the steam which is then mixed with the air prior to delivering the air to the carbureter. Since the temperature of the exhaust pipe will increase as the amount of exhaust gas increases, it follows that the rate of steam generation will closely approximate the rate of delivery of exhaust gas. Since the rate at which the exhaust gas is delivered depends almost directly upon the rate of fuel consumption, it follows that this arrangement will give a rate of steam generation closely proportional to the rate of fuel consumption, being, therefore, in this respect an ideal arrangement.

We will, furthermore, state that, in a simple embodiment of the features of the invention, we provide a water reservoir at a slight elevation above the water box to which the water reservoir is connected by a pipe or tube of such size as will not readily become clogged or obstructed by particles of dirt and the like which may be carried in the water. The delivery end of this pipe or tube is submerged by water contained

in the water box which, therefore, establishes automatically a water seal or weir. This will keep the elevation of the water always at the desired point without the use of complex mechanism, such as float valves, and also without the use of delicate devices, such as drip valves.

Turning now to a detailed consideration of the drawings, the cylinder block is designated in its entirety by the numeral 8. The exhaust manifold is designated by the numeral 9 and the intake manifold by the numeral 10. The intake manifold receives its gas from the central connection 11 under the control of the valve 12 in the carbureter 13. The fuel, such as kerosene or the like, is delivered to the carbureter by the line 14 from the fuel tank. The air or mixture of air and steam for the carbureter is delivered through the connection 15 in the direction of the arrow shown in Fig. 1. If air were to be delivered to the carbureter unheated, the connection 15 might be left open to the atmosphere, but in order to preheat the air and supply the same with steam, according to some of the features of the present invention, we have provided the constructions which we will now explain.

Reference particularly to Figs. 4 and 5 shows that the exhaust manifold 9 is surrounded by an air jacket in the form of an outer casing or wall 16, thereby providing the annular space 17 surrounding the exhaust manifold. A partition 18 extends lengthwise on both sides of the space 17, thereby dividing the same into lower and upper portions 19 and 20, respectively. The partition 18 extends forwardly a substantial distance within the space 17 so as to properly guide the air in its flow.

An air passage 21 extends upwardly on the inlet side of the engine, across the top of the engine, and downwardly on the exhaust side, and communicates with the lower passage 20 surrounding the exhaust manifold. Thus, the air is delivered into said lower passage and flows toward the right, as shown by the arrow in Fig. 1. This air then passes around the end of the baffle plate 18 and upwardly, as shown by the arrow in Fig. 1, and finally passes away from the exhaust manifold by way of a passage 22. This passage 22 extends upwardly and across the engine to the inlet side, and its lower end communicates with the passage 15, as shown in Fig. 1.

By the use of the foregoing construction, the air is preheated by the exhaust gas in a very effective and efficient manner. A simple form of construction is that illustrated in the drawings in which the passages 21 and 22 are provided by a special casting in which they are both formed.

The construction of the water box in which the steam is generated is shown in

detail in Figs. 5, 6, and 7. As a matter of convenience, the same constitutes a portion of a casting 23 which is built or set into the exhaust line 24, although it will be evident 5 that the water box can be provided in any other suitable manner. In the construction shown in Fig. 5, this casting includes the exhaust gas passage 25 and the chamber 26 located at one side of the same, the intermediate partition 27 separating said chamber from the exhaust gas passage. This construction presents the advantage of great 10 simplicity and low cost of manufacture. However, in the arrangement shown in Fig. 15 6, the casting 23 is modified to the extent that it is made in two parts with a separate removable partition 28 between the passage 25 and the water box 26. This partition 28 may be made of material having a very high 20 heat conductivity, such as aluminum or the like. This will increase the capacity of the steam generating unit without increasing its size or weight. The two portions of the steam generating element shown in Fig. 6 25 may be joined together by the use of bolts 29 with their nuts 30.

At a suitable point and at a suitable elevation with respect to the water box is a water tank 31. A tube or pipe 32 conducts the 30 water from the lower portion of this tank to the water box, terminating at the point 33 on the interior of the water box, as shown in Figs. 1, 2, and 7. The water will rise 35 within the water box to a level 34 slightly above the lower end of the tube 32, and as fast as the water is boiled out, it will be replenished through the tube. A clamp nut 35 serves as a convenient means for making a steam-tight connection between the tube 40 32 and the water box at the point where the steam tube enters the box.

The steam generated within the water box 45 passes out of the same by way of an opening 36 which communicates with an opening 37 in the lower portion of the air jacket around the exhaust manifold. Consequently, the 50 steam generated in the water box passes up and mixes directly with the air as the air is swinging around the end of the baffle plate 18. This will insure a very thorough mixture of the steam and the air. Thereafter the mixture of steam and air will travel a substantial distance in contact with the exhaust manifold, so that an additional 55 quantity of heat will be absorbed into the mixture, thereby superheating the steam and drying out the mixture. This still further enhances the beneficial action of the arrangement.

60 It is, of course, necessary to replenish the water in the tank 31 from time to time, and it is very desirable to be able to do this without disturbing the action of the remaining portions of the arrangement. It is desirable for this purpose to cut off or break

communication between the water tank and the tube 32 during the time the tank is being filled. For this purpose, we have provided a valve 38 between the tank 31 and the upper end of the tube 32. A spring 39 70 normally tends to close the valve 38. The filler cap 40 carries a downwardly extending pin 41 of such length that when the filler cap is fully inserted, as shown in Fig. 1, it will press against the valve 38 and open 75 the same against the force of the spring 34. On the contrary, when the filler cap is removed, the spring 39 will close the valve, and thus stop the flow of water to the tube 32. 80

As shown particularly in Figs. 1 and 2, a kink or bend 42 is formed in the tube 32. By the use of this kink or bend, the elevation of the lower end 33 of the tube can be regulated so as to raise or lower the level 85 of the water within the water box, thus simultaneously modifying the area of water in contact with the partition 27 of Fig. 5, or 28 of Fig. 6. If it be found, for example, that the engine is not getting sufficient 90 steam, the lower end of the tube may be raised, thereby raising the elevation of the water within the box, increasing the area of water in contact with the partition, and giving a greater steam production per cubic 95 foot of engine displacement.

While we have shown and described certain embodiments of our invention, still it will be understood that we do not limit ourselves to the same, except as we may do so 100 in the claims.

We claim:

1. In a device of the class described, the combination with an internal combustion engine having an exhaust manifold on one side of the cylinder block, an exhaust delivery pipe, and a carbureter on the other side of the cylinder block, of a water pot in contact with the exhaust pipe and heated thereby for the generation of steam or vapor, 105 means for maintaining a substantially constant level of water within such pot, a mixing jacket surrounding the exhaust manifold, there being a connection for the delivery of steam from the pot to said mixing 110 jacket, a U-shaped connection for delivering air from the carbureter side of the cylinder block up over said block to the mixing jacket for mixture with the steam in the presence of the hot manifold, and a U-shaped return 115 connection from the mixing jacket up over the cylinder block to the carbureter, both of said U-shaped connections being in contact with each other, substantially as described.

2. In a device of the class described, the combination with an internal combustion engine having an exhaust manifold on one side of the cylinder block, an exhaust pipe, and a carbureter on the other side of the 130

cylinder block, of a water pot in contact with the exhaust pipe and heated thereby for the generation of steam or vapor, a mixing jacket in contact with the exhaust manifold and heated thereby, there being a connection from the water pot to the mixing jacket for the delivery of steam to the latter, an air connection for the delivery of

air from the carbureter side of the cylinder block to the jacket for mixture with the 10 steam therein in the presence of the hot manifold, and a connection from said jacket to the carbureter, substantially as described.

TRUMAN B. FUNK.
WALTER L. CARVER.
